J. W. MOORE,
RADIATOR HANGER.

APPLICATION FILED OCT. 3, 1921.

UNITED STATES PATENT OFFICE.

JOHN W. MOORE, OF DETROIT, MICHIGAN.

RADIATOR HANGER.

1,425,891.

Specification of Letters Patent. Patented Aug. 15, 1922.

Application filed October 3, 1921. Serial No. 505,026.

To all whom it may concern:

Be it known that I, JOHN W. MOORE, a citizen of the United States of America, residing at Detroit, in the county of Wayne 5 and State of Michigan, have invented certain new and useful Improvements in Radiator Hangers, of which the following is a specification, reference being had therein to the accompanying drawings.

10 This invention relates to radiator hangers, and my invention aims to provide a hanger that may be adjustably connected to a wall or other support to adjustably hold various sizes and styles of radiators or heating devices. One or more hangers may be 15 employed for supporting a radiator in parallelism with a wall and the hanger is invisible to that extent that the design or appearance of the radiator is not marred or detracted from by the hanger.

20 My invention further aims to provide a radiator hanger having novel adjustments and parts which are constructed with a view of reducing the cost of manufacture and at 25 the same time retain those features by which the adjustments may be easily made, a radiator safely supported, and a radiator quickly demounted should occasion so require.

20 The construction entering into my invention will be hereinafter described and then claimed, and reference will now be had to the drawing, wherein

30 Figure 1 is a side elevation of the radiator hanger, partly broken away and partly in section, showing one form of radiator on the hanger;

Fig. 2 is a front elevation of the same;

Fig. 3 is a plan of the hanger and radiator;

40 Fig. 4 is a horizontal sectional view taken on the line IV—IV of Fig. 1;

Fig. 5 is a similar view taken on the line V—V of Fig. 1;

45 Fig. 6 is a side elevation of a radiator hanger supporting another type of radiator which necessitates a slight change in a portion of the hanger, and

50 Fig. 7 is a front elevation of the same with the radiator broken away to show a portion 50 of the hanger.

The radiator hanger comprises a substantially channel shaped wall bracket 1 having horizontal upper and lower walls 2 and 3 respectively and end flanges 4 which are 55 provided with transverse slots 5 adapted to receive screw bolts 6 or other fastening

means so that the bracket 1 may be attached to a wall or other support. The slots 5 will permit of lateral or sidewise adjustment of the bracket 1 so that said bracket may be correctly positioned relative to the columns 7 of a radiator to permit of said radiator being supported without any strain on plumbing connections with said radiator. As will hereinafter appear, it is necessary that the 60 bracket 1 have a defined relation to the columns of the radiator in order that fastening devices of the bracket may extend between the columns of the radiator.

65 The walls 2 and 3 of the bracket 1 are 70 slotted, as at 8, and suspended from the top wall 2 and extending through the slot 8 in the wall 3 is an adjustable suspension member 9 in the form of a bolt which has a head 10 engaging the upper face of the 75 wall 2 and its threaded end extending through the wall 3.

80 Loose on the threaded end of the suspension member 9 is the barrel 11 of a hook shaped support 12, said support being in the form of a blade which is slidable in a vertical slot 13 provided therefor in the lower portion of the bracket 1, said slot communicating with the slot 8 of the lower wall 3, as shown in Figs. 4 and 5. The blade 12 85 is adapted to extend between columns of the radiator 7 so that connecting portions 14 of the radiator columns may rest on the hook shaped support. As shown in Fig. 1 the radiator is of such construction that two of 90 its columns may bear against the bracket 1 with the connecting portions of the columns resting on the hook shaped support. This is also true in connection with the radiator shown in Figs. 6 and 7, but here it is necessary to make the hook shaped support more pronounced as to a hook shaped configuration in order that the support may engage under the bottom header 15 of the radiator 95 while one or more columns thereof bears 100 against the bracket 1.

105 The blade of the support 12 may readily have its rear edge rolled to provide a barrel or sleeve 11 and this barrel, adjacent its upper end, has a transverse slot 16 providing clearance for a nut 17 screwed on the threaded end of the suspension member 9. The nut is preferably rectangular so that a facet thereof may bear against the bracket 1 and prevent rotation of the nut while the radiator 110 is being supported and the facet of the nut may cooperate with the barrel 11 in bracing

the support 12 relative to the wall bracket 1. It is through the medium of the nut 17 that the support 12 may be raised or lowered on the suspension member 9 to support the 5 radiator at a desired elevation relative to the wall bracket, and in some instances the nut 17 may engage the lower wall 3 and the head 10 of the suspension member 9 engage the upper wall 2, thus permitting of the nut 10 and head assisting in supporting the weight 10 of the radiator. The slots 8 in the walls 2 and 3 may permit of the radiator being shifted to and from the bracket 1 and supported perfectly plumb relative to any wall 15 or support that may be out of plumb.

Adjacent the upper end of the bracket 1 is a rectangular opening for the rectangular portion 18 of a tie rod 19, said tie rod having a head against the rear face of the bracket 20 1 and the rectangular portion of the tie rod prevents rotation thereof relative to the bracket. The tie rod 19 is adapted to extend between the same columns of the radiator, between which the hook shaped support 25 12 extends, and on the front end of the tie rod 19 is a sleeve nut 20 provided with an oblong washer 21. The oblong washer 21 may be positioned to engage radiator columns that are close or far apart and when 30 the sleeve nut 20 is tightened the washer 21 will be wedged between and against the radiator column walls to bind or clamp the radiator columns against the bracket 1.

From the foregoing it will be observed 35 that the radiator wall hanger has many adjustments by which a radiator may be properly supported relative to a wall or radiator connections and the number of hangers employed depends upon the length and over-

all size of the radiator. With the bracket 1 40 and support 12 cut and pressed from metal, by suitable dies or the like, the hanger can be manufactured at a comparatively small cost, and while in the drawing there is illustrated a preferred embodiment of my invention, it is to be understood that the structural elements are susceptible to such changes as fall within the scope of the appended claim.

What I claim is:—

Means for supporting a radiator or the like, comprising a bracket having upper and lower horizontal walls, said bracket having a longitudinal slot meeting an opening in the lower horizontal wall of the bracket, a 55 blade - like radiator support extending through the slot of said bracket and having a rolled edge forming a barrel behind said bracket, which barrel extends through the opening in the lower horizontal wall of said 60 bracket, a suspension member carried by the upper horizontal bracket wall and extending into the barrel of said radiator support, the barrel of said radiator support having a slot 65 therein, a nut in the slot of the barrel of said radiator support and engaging said suspension member to hold said radiator support relative thereto, and means carried by the upper end of said bracket to cooperate with said radiator support in holding a 70 radiator.

In testimony whereof I affix my signature in presence of two witnesses.

JOHN W. MOORE.
